UNITED STATES PATENT OFFICE.

ARMINDA BEATRICE RUSH, OF NEW YORK, N. Y.

WINDOW-SHADE GUIDE.

No. 863,655.

Specification of Letters Patent.

Patented Aug. 20, 1907.

Original application filed June 5, 1905, Serial No. 263,801. Divided and this application filed December 22, 1906. Serial No. 349,093.

To all whom it may concern:

Be it known that I, ARMINDA BEATRICE RUSH, a citizen of the United States, residing at New York, in the county of New York and State of New York, have 5 invented a new and useful Improvement in a Window-Shade Guide, of which the following is a specification.

This invention relates to a window shade guide originally shown and described in an application for patent filed June 5, 1905 and given Serial Number 263,801 of 10 which this is a divisional application.

The invention consists of a guide formed of a single piece of metal bent upon itself to form a front and a back plate, the upper and lower edges of the front plate being bent outwardly and the upper and lower edges 15 of the back plate being rolled over to form sleeves.

In the accompanying drawings, Figure 1 is a perspective view showing my device in use, Fig. 2 is an enlarged sectional view on the line 2—2 of Fig. 1, Figs. 3 and 4 are detail perspective views of the front and rear 20 faces respectively of one of the guides, Fig. 5 is a sectional view on the line 5—5 of Fig. 6, Fig. 6 is an edge view of a guide showing the position the shade stick occupies when raised to its highest point, Fig. 7 is a detail view of the blank from which the guides are 25 formed.

In the drawings A represents my guide and B the blank metal from which the guides are made. The blank B is bent centrally upon itself into substantially

a U shape thereby forming between its two faces a guideway A' and the guide thus formed has a front face 30 C and a rear face D. The face C of the guide has its upper and lower edges beveled to bend outwardly as at C' thereby preventing the said edges from coming into direct contact with the shade and injuring the same when moved up and down between the two faces. The 35 rear face D has its upper and lower marginal portions bent over to form sleeves D' which sleeves form guideways through which nails E can be passed for the purpose of securing the guide in position. The lower sleeve D' and the lower beveled edges C' also form a 40 stop for the shade stick E' as shown in Fig. 6.

Having thus fully described my invention, what I claim as new and desire to secure by Letters Patent, is:—

1. A shade guide formed of a piece of metal bent upon 45 itself to form a front and rear face, opposite edges of the rear face being rolled over to form sleeves, and opposite edges of the front face being beveled as and for the purpose set forth.

2. A shade guide substantially U shape, the front face 50 having its upper and lower portions bent outwardly and the rear face having its upper and lower edges rolled over to form guides for a fastening means.

ARMINDA BEATRICE RUSH.
